UNITED STATES PATENT OFFICE.

JOHN B. FITCH, OF NEW HAVEN, CONNECTICUT, ASSIGNOR TO THE
W. & E. T. FITCH COMPANY, OF SAME PLACE.

DESIGN FOR A SNAP-HOOK.

SPECIFICATION forming part of Design No. 26,109, dated September 29, 1896.

Application filed August 17, 1896. Serial No. 603,087. Term of patent 14 years.

To all whom it may concern:

Be it known that I, JOHN B. FITCH, of New Haven, in the county of New Haven and State of Connecticut, have invented a new Design 5 for Snap-Hooks; and I do hereby declare the following, when taken in connection with the accompanying drawings and the letters of reference marked thereon, to be a full, clear, and exact description of the same, and which said 10 drawings constitute part of this specification, and represent, in—

Figure 1, a plan view of a snap-hook containing my improved design; Fig. 2, a reverse plan view thereof.

15 My invention relates to a design for snap-hooks; and the design consists in the configuration and ornamentation as herein shown and described.

As herein shown, my newly-designed snap-hook consists in a hook A, a shank B, and an eye C, the juncture of the shank B and eye

C being ornamented by raised leaf-like extensions D D, starting from the upper face of the shank and curving outward onto the upper face of the inner bar of the eye C, and 25 by similar raised leaf-like extensions D' D', starting from the lower face of the shank and curving outward onto the lower face of the inner bar of the eye, all as shown in the accompanying illustrations. 30

I claim—

The design for snap-hooks as herein described, and shown in the accompanying illustrations.

In testimony whereof I have signed this 35 specification in the presence of two subscribing witnesses.

JOHN B. FITCH.
